UNITED STATES PATENT OFFICE.

LYMAN C. HUFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

APPARATUS FOR REMOVING CARBONACEOUS MATERIAL FROM OIL-TREATING APPARATUS.

Application filed June 15, 1925, Serial No. 37,122. Renewed August 3, 1928.

This invention relates to improvements in apparatus for removing carbonaceous material from oil treating apparatus and refers more particularly to means mounted within 5 the reaction chamber, comprising a heavy metal flexible element suspended within substantially the central portion of the chamber and enclosed by spaced upright rods, which latter form in effect an open-ended cage. 10 Another length of flexible element may have one end disposed adjacent an end of the chamber and stretched around the upright rods in a series of vertically spaced layers. The lengths of flexible metal element are adapted 15 to be suspended within the interior of said chamber and in the bed of carbonaceous material deposited therein. These flexible metal elements are adapted to be withdrawn from an end of said reaction chamber when the oil 20 treating operation has been completed.

In practice, the withdrawal of the flexible elements from the end of the reaction chamber will not only disrupt the carbon formation, but at the same time will assist in with- 25 drawing large amounts of carbonaceous material up to say sixty per cent.

The invention described in this application is in part an improvement on the subject matter of co-pending application filed by me 30 in the United States Patent Office, Serial No. 614,954, filed January 26, 1923, which has matured into Patent No. 1,548,004 granted July 28, 1925.

In the drawings, Fig. 1 is a cross sectional view of a reaction chamber illustrating my 35 invention, said view being taken on line 1—1 of Fig. 3 looking in the direction of the arrows.

Fig. 2 is a cross sectional view through the 40 chamber illustrating a carbon bed with the cage and inner flexible element removed.

Fig. 3 is a cross sectional view taken on line 3—3 of Fig. 1 looking in the direction of the arrows.

45 Referring in detail to the drawings, the enlarged chamber 14 may take the form of an enlarged chamber vertically disposed, having an inlet 13, receiving heated oil which has been heated to substantially a conversion tem- 50 perature in a pipe still, for instance, not shown. Immediately upon being introduced into the interior of the chamber 14, substantial separation of lighter fractions will take place, and the vapors liberated from the heat- 55 ed oil may be discharged through the outlet

12, which may in turn discharge the vapors to the usual dephlegmator and condenser, not shown. Coincident with the liberation of the vapors, carbon particles will be precipitated and will eventually build up a substantial 60 body in the chamber. Unvaporized liquid residue may from time to time be withdrawn through the residue draw-offs 11, which may be controlled by valves 10, it being understood that these residue draw-offs are disposed at varying heights on the exterior wall 65 of the chamber, in order to withdraw the liquid residue from various heights, at the same time compensating for the gradually increasing height of the carbon bed within 70 the chamber.

It is understood, of course, that in the class of oil treatment in which my invention particularly belongs, there is no substantial precipitation and accumulation of carbon in the pipe still. It is desired that substantial separation of vapors take place within the chamber 14, the precipitated carbon being deposited therein and gradually building up within 75 the chamber. Any desired pressure may be maintained in the reaction chamber 14 from three to several hundred pounds per 80 square inch.

Referring now to some of the features of the present invention, within the enlarged chamber 14 and attached to the inner wall thereof, are spaced upright hooks 23, of which there may be any number, the arrangement being such that there may be any desired 85 number of layers of hooks, each layer being disposed at different vertical heights in the chamber. A plurality of spaced uprights rods 101 which may have hooked base portions 102 are placed in the interior of the chamber in the form of an open-ended cage 90 substantially centrally thereof. Within the space formed by the spaced rods 101 may be spirally wound a metal flexible element 103, which may have an eye-bolt 104, as shown. This metal flexible element may take the 95 form of a steel cable, chain or the like. The element 103 may be fastened at its points of contact with the supporting uprights 101 by means of the small tie wires 105, these tie wires being of say twelve to fourteen gauge. 100

A second metal flexible element 106 may be wound in layers outside or exterior of the supporting uprights 101, the arrangement being such that the path of travel is outwardly from the point "a" toward the point "b", the 110

points of contact between the flexible element 106 and hooks 23 being connected by means of small tie wires 105' similar to the tie wires 105. The metal flexible element is passed 5 from hook to hook on this lower layer until it is attached to all of the hooks, at which time it may be passed upwardly, as shown at 108, in an inwardly extending direction, where it is again wound in a gradually outwardly pro- 10 gressing direction and attached to a second layer. It is, of course, understood that this arrangement may be followed and any desired number of layers may be formed. The rods 101 may be held in place by means of the 15 horizontally extending tie wires 107, having their outside ends attached to the hooks at 23. During the operation of an oil treating process, precipitated carbon will accumulate and settle upon the lower coils of the metal flexible 20 element and as it builds up, the lengths of the metal flexible element and uprights extending within the chamber will be positioned in the body of accumulated carbon. After the apparatus has been shut down and a sufficient 25 time elapsed for cooling, the lower manhole plate 16 closing the lower end, or an upper manhole plate, not shown, closing the upper end, or both, may be opened and the portion 30 104 on the metal flexible element 103 may be attached to any suitable mechanism for exerting a pulling force thereon, such as a winch.

As the metal flexible element 103 is being forcefully withdrawn from the chamber 14, the light gauge tie wires 105 will successively 35 break, allowing the metal flexible element to be easily withdrawn. This will disrupt and withdraw the carbon from the central portion of the chamber, forming an opening through said bed. The uprights 101 may be then re- 40 moved, which leaves a very pronounced opening, as clearly shown at 109 in Fig. 2, through the carbon bed.

The metal flexible element 106 is then withdrawn, which disrupts the remainder of the 45 carbon bed and facilitates its eventual withdrawal. The opening formed in the bed of carbon allows for the entrance of a workman, if found desirable, into the interior of the chamber, in order to assist the breaking of 50 the bond between the particles forming the bed.

It has always been a difficult matter to remove a carbon formation of this character when it is permitted to accumulate in substantially solid form and where there is an unbroken carbon formation, considerable time is lost in disrupting said formation and removing it from the chamber. By means of the apparatus of the present invention, the 55 carbon accumulation can be readily broken

up and removed from the chamber and the apparatus again made ready for operation within a comparatively short time. In addition, the withdrawal of the flexible element 103 and uprights 101 not only disrupts the central 85 portion of the carbon bed, but also removes the carbon, forming a central opening through the carbon bed.

I have shown and described the metal flexible elements as being wound in spiral or coil fashion. It must be understood, however, that the winding of the metal flexible element may take any desired form; for instance, the flexible elements may be wound spirally, zig-zag, coiled, star-shaped, or in any other suitable manner.

I have shown and described a vertical reaction chamber, but it must be understood that I may use a horizontal or other suitable type 80 of reaction chamber.

It is to be understood that the ends of the flexible elements which are to be removed through the ends of the chamber may be positioned at the upper or lower end of the chamber and withdrawn from either the top or bottom of the chamber. When withdrawn through the top end of the chamber, the bottom end may be opened to allow a substantial portion of the disrupted carbon to fall 90 out.

I claim as my invention:

1. In an oil conversion apparatus, the combination with an enlarged chamber having suitable walls and in which chamber carbon is precipitated and accumulated, of flexible metal elements releasably supported within said chamber, one of said elements extending through substantially the central part of the chamber, spaced uprights forming a cage surrounding said element, and another of said flexible elements extending through the chamber exteriorly of the uprights, the flexible elements being adapted to be withdrawn from the chamber to disrupt carbon precipitated therein.

2. In an oil apparatus, the combination with an enlarged chamber having suitable walls and in which chamber carbon accumulates, of flexible metallic elements releasably supported within said chamber, one of said elements extending through the central part of the chamber, a plurality of spaced members positioned about said element, and another of said flexible elements extending through the chamber exteriorly of said spaced members, said flexible elements being adapted to be withdrawn from the chamber to disrupt carbon deposits accumulated therein.

LYMAN C. HUFF.
